DESIGN FOR A TAPPING SLIPPER

Benjamin Brodick, New York, N. Y.

Application October 25, 1939, Serial No. 87,847

Term of patent 3½ years

To all whom it may concern:

Be it known that I, Benjamin Brodick, a citizen of the United States of America, residing in New York city, in the Borough of Manhattan, county and State of New York, have invented a new, original, and ornamental Design for a Tapping Slipper, of which the following is a specification, reference being had to the accompanying drawing, forming part thereof, wherein:

The design consists of a piped ornamented vamp section combined with a rear band of rebounding nature, as shown.

I claim:

The ornamental design for a tapping slipper, substantially as shown and described.

BENJAMIN BRODICK.
